UNITED STATES PATENT OFFICE.

CHARLES E. McMANUS, OF NEW YORK, N. Y., ASSIGNOR TO CROWN CORK & SEAL COMPANY, INC., OF NEW YORK, N. Y., A CORPORATION OF NEW YORK.

APPARATUS FOR MAKING COMPOSITION-CORK SHEETS.

Application filed June 5, 1923. Serial No. 643,553.

My invention relates to apparatus for making composition cork sheets, and more particularly to an apparatus of this type in which the material is produced by a continuous operation involving not only the delivery of succeeding charges of the granular cork with its thin coating of adhesive or binding material, and the substantially uniform compaction thereof within the desired bulk, but the subjection of the compacted composition to an elevated temperature and other conditions which will ensure the setting of the adhesive or other binding material in a manner to ensure the desired homogeneity of the product and a resiliency approximating that of natural cork.

Heretofore in the production of cork sheets, it has been the practice to form such sheets by means of molds, the capacity of which is such as to produce slabs of the material, such molds having the composition cork mechanically delivered thereto and compacted therein, by a packing machine, the molds thereafter being passed through a baker or vulcanizer and a cooler before being opened for the purpose of drawing the slabs therefrom. This cooling operation is in the nature of a curing process not only permitting the adhesive or other binding material to set, but conditioning the composition so that it may be subsequently cut into any form which may be desired, either into sheets or blocks from which various articles of manufacture may be made.

Because of the expansive force developed as a result of the application of heat to the mass within the molds, these molds must possess great rigidity, and the handling of the same is a matter of considerable difficulty and requires considerable time, which is a factor of much importance in the production of material which must be cheaply produced to meet competition with the natural product. Composition cork has the advantage, however, that it may be handled in regular sizes and may be made in sufficiently large sizes and of uniform thickness, thus permitting a reduction in the cost of subsequent handling and the avoidance of waste in a degree which is present when using natural cork.

In apparatus embodying my invention, the coated cork granules are delivered to

means forming a continuous mold in succeeding substantially uniform charges or batches, by a mechanism which forces each charge into intimate relation with preceding charges, while at the same time compacting it within the mold which is of substantially the same dimensions throughout, so that succeeding charges will be brought to the same dimensions with relation to the entire strip produced in the apparatus.

The compacted mass is advanced by a step by step movement under conditions which will hold it compacted, and while being so held, the mold forming means pass through a zone of high temperature in which the adhesive is brought to a tacky state, and with some adhesives, partially set, and thereafter through a low temperature zone, in which the mold and its contents are partially cooled, and the adhesive or binding material finally set so that as the cork composition strip is delivered from the machine, it is a homogeneous strip of substantially uniform dimensions throughout. This strip, by reason of the final cooling stage in its production, is in a condition to permit the mold forming elements to be readily separated therefrom, the cooling operation having progressed to a point adjacent these elements where there is no likelihood of a bonding action between the cork composition and the wall of the mold. Furthermore, as the mold forming elements pass from engagement with the cork strip, when it has been conditioned as above, there is no tendency of the composition to expand when relieved of the confining pressure from said elements, thus ensuring a fairly smooth flat surface at all faces of the strip.

In compacting cork composition, even by succeeding operations and in batches of substantially the same volume, and also limited as to volume so as to conform to the capacity of the machine in compacting same, considerable resistance is developed between the material and the walls of the mold, which if the batches are too large, will prevent a satisfactory compaction of the mass. While in a continuous mold machine of the character shown in the accompanying drawings, wherein the mold may be of a length of sixty, seventy, or more feet as to those elements forming the mold

space, the friction engendered will be very great and may be relied upon to offer sufficient resistance to prevent relative movement of the strip and of the mold forming elements, thus developing that resistance required for compacting the fresh batches as they are delivered to said elements. I prefer, however, to so construct the apparatus that said mold forming elements will be positively held against movement during the compacting interval of each cycle of the machine, and will be positively advanced during that portion of the cycle during which the compacting member is receding 10 from a compacted or partially compacted charge of the composition, and a succeeding charge is being delivered in relation thereto.

I also preferably so construct the apparatus that the cork composition receives an initial compaction prior to its delivery to the mold forming elements, these elements completing the compaction, and holding it while passing through the high and the low 20 temperature zones.

The invention consists primarily in an apparatus of the character described embodying therein two oppositely disposed, endless carriers, the adjacent reaches of 30 which extend in substantially parallel relation to each other, a sequence of independent mold forming elements supported by said carriers respectively and adapted to be brought thereby so as to abut against each other, the elements upon said carriers respectively being spaced apart to form a continuous mold space, and flanges closing the opposite edges of said mold space, means whereby said carriers may have simultaneous, similar movement imparted thereto, means compacting and delivering composition cork to within said mold space, and a heated chamber through which said mold forming elements are passed after receiving 40 said composition cork; and in such other novel features of construction and combination of parts as are hereinafter set forth and described, and more particularly pointed out in the claims hereto appended.

50 Referring to the drawings,

Fig. 1 is a condensed side view of an apparatus embodying my invention, the central portion of the apparatus being broken away;

55 Fig. 2 is a condensed plan view thereof;

Fig. 3 is a condensed vertical section longitudinally of the machine; and

Fig. 4 is a section on the line 4—4 of Fig. 3.

60 Like numerals refer to like parts throughout the several views.

In the embodiment of my invention shown in the drawings, I employ two sets of endless carriers or chains 10 and 11, the former of which pass about two pairs of

sprocket wheels 12 and 13 arranged adjacent opposite ends of the machine respectively, and the latter of which pass about two pairs of sprocket wheels 14 and 15 also arranged adjacent opposite ends of the machine. The shafts carrying the pairs of sprocket wheels 13 and 15 are preferably geared together so as to ensure the desired unidirectional and uniform movement under similar conditions of the chains of each set, these gear wheels being shown at 16 and 17 respectively.

The lower reach of the chains of the set 10 and the upper reach of the chains of the set 11, or the adjacent reaches of the carrier chains, or carriers, are, by reason of the positioning of the various sprocket wheels, maintained in substantially parallel spaced relation, it being desirable, however, to provide suitable backing members or supports for the mold forming elements carried by these chains, which will be more particularly referred to hereinafter, for the two-fold object of maintaining this parallel relation and preventing the separation of 90 mold forming elements as a result of the expansion, under heat, of the cork composition in the mold space between said elements.

Each set of chains 10 and 11 has secured thereto a sequence of mold forming elements, those upon the chains 10 being indicated at 18 and those upon the chains 11, at 19, the parallel adjacent reaches of the chains of each set being spaced apart sufficiently to form a mold space between the elements 18 and 19 as these elements are brought into cooperating relation by the portion of said carrier chains carrying same entering the adjacent parallel reaches of 105 said chains. The elements naturally separate as the chains pass about the sprocket wheels with which they co-operate.

The mold space thus formed is closed at the opposite or side edges by flanges upon the ends of the elements 18 or 19, these flanges in the drawings being shown at 20 and upon the elements 18, although it is apparent that so long as these end flanges which form the sides of the mold are so proportioned as to close the space between said elements, it is immaterial whether they are formed upon one or the other of the mold elements or upon both of said elements.

By mounting the mold forming elements upon carriers 10 and 11 passing about sprocket wheels as shown, said elements are permitted to have simultaneous and similar movement during the operation of the machine, so that as each charge of the cork composition is delivered to within the mold space, succeeding mold forming elements will replace those utilized for forming the mold space thus filled. In this manner there is no interruption in the mold space,

the effect being a continuous mold, the elements forming which are repeatedly brought into their co-operating relation to permit the charging of the mold, and out of this relation to permit the discharge of the product.

In the formation of strips or sheets of compacted cork granules having a very thin surface coating of adhesive or binder, a liquid-tight joint is not necessary between 10 succeeding mold forming elements, or at the ends of the elements upon the oppositely disposed carriers as the matter delivered within the mold space is never fluid. In fact a loose fit affords a vent for gases which 15 may be released within the mold while it is being subjected to high temperatures, thus permitting greater density in the product by the elimination of small voids resulting from the presence of gas within the mold. 20 This is true particularly as to the surface of the product, where the gas would have the greatest tendency to accumulate. This, however, is a matter of minor importance, particularly as the surface of the strip or 25 sheet will always have more or less the surface grain of the metal of the mold.

The shafts of the sprockets 12 and sprockets 13 and sprockets 14 with the sprockets 15 are spaced a considerable distance apart 30 in order to ensure the mold elements and the composition cork in the mold space formed thereby to be subjected to a high temperature zone for a sufficient interval to thoroughly heat the entire mass of composition cork so as to fuse or otherwise condition the 35 adhesive or binder to cause the cork granules to be firmly cemented together. The carrier chains and the mold forming elements are also passed through a low temperature zone, 40 after leaving the high temperature zone, for an interval of time sufficient to permit the adhesive or binder to fully set, and surface shrinkage of the composition to be sufficiently great to prevent the mass expanding 45 when relieved of the pressure from the mold forming elements. The distance between said sprockets may, according to the dimensions of the sheet, vary from sixty to one hundred twenty-five feet.

Throughout a portion of the length of the carriers 10 and 11 and the sequence of mold forming elements 18 and 19 carried thereby, they pass through a high temperature zone indicated at 21 having suitable heating media as the gas burners 22 therein, said carriers and elements after leaving said high temperature zone passing through a low temperature zone 23 extending to the discharge point of the machine. The relative length of these high temperature and low temperature zones may be varied according to the adhesive or binder used and the dimensions of the sheet or strip being formed.

It is well known to workers in the arts

utilizing composition cork, that the time required to properly condition the adhesive or binder is such as to place a limitation upon the thickness, or cross-sectional area of the mass of composition, since sufficient time 70 must be allowed for the heat to penetrate the entire mass of composition, and yet the interval must not be sufficiently great to cause the heat to injure the cork granules adjacent the surface of the mass. Ordinarily the maximum thickness of the mass to secure the best results should not exceed 75 two inches and a thinner mass is preferable.

Adjacent the sprocket wheels of each pair 12 and 14, and at a point where the elements 18 and 19 converge toward and are entering into, the adjacent parallel reaches of the carrier members or chains 10 and 11, I provide a charging and compacting mechanism 80 by which substantially uniform quantities of the cork composition are delivered in succeeding charges to the mold space formed between the elements 18 and 19 and the side flanges 20 upon either or both of these elements. This mechanism comprises a throat 85 90 24 of a width corresponding with that of the mold space formed by the elements 18 and 19, and having converging top and bottom walls so as to cause the gradual compaction of the mass of composition and its delivery 95 in compacted condition to within the mold space. One end of this throat has slidably mounted therein a piston 24' moving in what may be termed a rectangular cylinder. A measuring device 25 communicates with said cylinder so as to deliver a charge in advance of the piston 24 during each cycle of operations of the machine.

In the accompanying drawings, I have shown merely a conventional measuring device consisting of radially spaced vanes 26 105 adapted to receive the cork composition from a suitable hopper 27. The vanes 26 are actuated by an intermittent mechanism consisting of a ratchet wheel 28 acted upon by a pawl 29 carried by a swing frame 30 mounted upon the shaft of said ratchet wheel and actuated by means of a link 31 connected with the pitman 32 for actuating the piston 24', or one of the trunnions of 110 said piston. The teeth of the ratchet wheel 28 are so set that during the compacting stroke of said piston 24', the measuring device will be inoperative, but will be actuated during the return or inoperative stroke of 115 the piston. The graduated portion of the throat is shown at 33 and the so called cylinder at 34.

Owing to the compressibility inherent to the material of the composition, it has a 125 tendency, when delivered to within the mold space, to expand immediately after compaction, and when subjected to heat, this tendency is materially increased, the last condition being relied upon to secure the desired 130

binding of the granules together and uniform density in the production. Where the mold is formed of a sequence of independent co-acting elements supported by a flexible carrier, there is naturally a tendency of these elements to separate under the expansive force exerted by the composition, which would result in an absence of the desired density, and a variance in the dimensions as to thickness, of the product.

To correct the above condition, I provide a plurality of backing members or supports 35-36, the former of which is adapted to engage the mold forming elements 18 while they are being passed along the lower reach of the chains 10, and the latter of which is adapted to engage the mold forming elements 19 upon the upper reach of the chains 11 parallel with the bottom reach of the chains 10. The number of such backing members or supports will vary with the width of the elements 18 and 19, the purpose of said members being to preserve the parallel relation of the cooperating elements while they are forming the mold space, and hold them against likelihood of being separated by pressure from within the mold. It is desirable to provide anti-friction rollers 37 and 38 upon each of the elements 18 and 19 respectively, adapted to engage the backing members or supports for the purpose of minimizing wear and reducing friction at this point of the machine.

The piston 24' is actuated by means of a crank shaft, one of the cranks 39 of which is connected with the pitman 32 and another crank 40 of which, is connected by the rod 41 with a crank disk 42 upon the shaft adjacent one of the pairs of sprocket wheels, the pin of said disk being so set with relation to a mechanism, for actuating the carrier chains 10 and 11, as to impart a return, inoperative movement to the piston 24' while the carriers are being advanced, and a direct, compacting movement to said piston while said carriers are held against movement by said mechanism.

The mechanism for imparting an intermittent advancing movement to the carriers 10 and 11 consists of a Geneva movement, the disk 42 co-operating with a Geneva gear 43 forming one element of this movement. The shaft of said gear 43 has mounted thereon a spur gear 44 in mesh with the gear 17. The disk 42 has associated therewith a plate 45 having thereon a single pin 46 adapted to co-operate with the gear 43. The disk 42 and the plate 45 may be driven in any desired manner as by means of an ordinary belt and pulley drive indicated at 47.

At 48 I have shown the gas feed pipe for the burners within the chamber 21.

While I have shown the Geneva gear driving movement as being associated with one of the sprocket wheels 15, it is apparent

that this movement may be shown toward the end of the machine adjacent the compacting throat 24, if it be desired to avoid a long connecting rod 41.

Preferably the cranks 39 and connecting rods 32 are duplicated upon opposite sides of the machine.

The operation of the herein described mechanism is substantially as follows:—

In starting a run of the machine, a charge with the first cycle of operations of the machine is delivered from the measuring device into the cylinder 34 between the piston 24 and the graduated opening in the throat 33. During a part of this interval the chains 10 and 11 and the mold forming elements 18 and 19 carried thereby, are being moved by the Geneva gear mechanism, this movement being away from the throat 33 as to the two adjacent reaches of said chains and the mold elements secured thereto.

Upon the next cycle of the machine, the crank disk 42 and parts actuated thereby will impart a direct reciprocation to the piston or plunger 24', or a movement towards the mold elements, thus forcing the charge of granular cork, coated as herein described, toward and into the throat 33. The converging top and bottom walls of this throat will offer resistance to the movement of the greater portion of this charge, so that there will be a partial compaction of the mass while within the throat. Upon the following cycle the above operations will be repeated, the charge in this cycle and in all succeeding cycles being forced into engagement with the charge or charges previously compacted in the throat 33 and imparting movement thereto towards and to within the mold space between the mold forming elements 18 and 19 and their end flanges 20. After the delivery of the initial charge to within the mold space, all charges will be compacted in substantially the same degree subject, however, to slight variation because of possibility of succeeding charges not being of exactly the same bulk.

The first few charges delivered into the mold may not be sufficiently compacted to secure commercially satisfactory results, owing to the fact that the length of each charge does not exceed one and a half or two inches when compacted, and the frictional resistance between the charge and the walls of the mold may not offer that resistance necessary to secure the desired compaction in these first few charges. As the length of the material in the mold becomes greater, however, this resistance will of itself be sufficient to ensure the desired compaction of the mass so that thereafter, in the continued operation of the machine, there will be no difficulty in securing the desired initial density as a result of the mechanical compaction of the composition.

1 In the accompanying drawings, the scale is so small as to make an exact showing of conditions impossible, and the spacing of the parts as shown is not accurate. This, however, is a matter of mere mechanical detail.

2 As the various mold forming elements 18 and 19 come together in parallel planes, they will of themselves develop certain pressure upon the composition within the mold, and
10 check any tendency it may have to expand to a material extent after each charge is filled into the mold.

3 The cork composition itself when delivered from the measuring device, is in loose granules coated with adhesive or binding material conditioned so as to have little or no tendency to cause the granules to cohere. The initial compaction, however, will cause the granules to cohere with sufficient strength
20 to prevent the separation of particles therefrom in the short distance between the discharge end of the throat 33 and the point where the mold forming elements close upon the mass of compacted granules.

4 The various elements 18 and 19 passing along the adjacent reaches of the chain 10 or 11, (the carriers), will be advanced by a step by step movement, the quantity of movement being measured by the effective stroke
30 of the piston or plunger 24', whether this advance be a positive mechanical movement as shown, or as a result of the movement of the compacted granular cork into the mold space as a result of the frictional engagement between this material and the walls of said space. The positive mechanical movement shown is preferable as ensuring the desired extent of compaction of all charges.
40 It is apparent that while the machine is in operation, the cork composition will pass in a continuous sheet to within the mold space, notwithstanding that the charging of the mold is by an intermittent operation and with succeeding charges.

5 As the elements 18 and 19 while forming the mold space thus progress with a step by step movement, they are brought successively through the high temperature zone 21 where
50 the heat will have the effect of properly conditioning the adhesive so as to form the desired intimate bond between the different cork granules and at the same time cause the readjustment of these granules with relation to each other as a result of expansion of the mass under heat, to secure the desired density of the product. Separation of the mold elements during this expansion is prevented by the backing members or supports 35 and 36.

6 As the various mold elements leave the high temperature zone 21, the cork granules will be substantially permanently bonded together, but if the mold were opened at this time, the cork sheet or strip would expand,

since the adhesive has not fully set and the entire mass is still more or less plastic. It is for this reason that I provide a low temperature zone 23 through which the mold elements are carried so as to permit the partial cooling of the mass to permit it to take a more or less permanent set and permit shrinkage, particularly of the portion of the composition adjacent the surface of the strip or sheet, with the two fold object of utilizing this portion of the strip to check the tendency of the entire mass to expand, and at the same time permitting the separation of the mold forms without likelihood of the surface of the composition adhering thereto.

7 It is apparent that the mass of composition cork will be discharged from the apparatus in the form of a continuous strip or sheet which will have a high degree of flexibility and substantially uniform density throughout. Such material has none of those voids characteristic of natural cork, so that it may be readily separated into blocks or sheets, each of which will be free from surface voids, or from openings extending entirely therethrough, thus particularly adapting the product for use in the production of gaskets for use in gas engines or in other connections, cushions for bottle caps, and various analogous purposes in the arts.

8 While the movement of the mold forming elements 18 and 19 away from each other as a result of the passage of the carrier 100 chains 10 and 11 of each pair about the sprocket wheels 13 and 15, will ordinarily ensure the free movement of the compacted, vulcanized or baked and partially cooled strip or sheet (shown at 49) from the machine, I may provide stripper members 50 and 51 for ensuring a complete separation of the sheet or strip 49 from the succeeding elements 18 and 19.

9 It is not my intention to limit the invention to the precise details of construction shown in the accompanying drawings, it being apparent that such may be varied while still permitting the production of a continuous sheet or strip of the composition cork material as a result of the intermittently movable separable mold forming elements mounted upon continuous carriers, the adjacent reaches of said carriers being passed progressively through high and low 105 temperature zones which secure the desired effects as above stated.

10 Having described the invention, what I claim as new and desire to have protected by Letters Patent, is:

11 1. An apparatus of the character described, embodying therein two oppositely disposed, endless carriers, the adjacent reaches of which extend in substantially parallel relation to each other, a sequence of independent 120

5 mold forming elements supported by said carriers respectively and adapted to be brought thereby so as to abut against each other, the elements upon said carriers respectively being spaced apart to form a continuous mold space, and flanges closing the opposite edges of said mold space, means whereby said carriers may have simultaneous, similar movement imparted thereto, 10 means compacting and delivering composition cork to within said mold space, and a heated chamber through which said mold forming elements are passed after receiving said composition cork.

15 2. An apparatus of the character described, embodying therein two oppositely disposed, endless carriers, the adjacent reaches of which extend in substantially parallel relation to each other, a sequence of independent mold forming elements supported by said carriers respectively and adapted to be brought thereby so as to abut against each other, the elements upon said carriers respectively being spaced apart to form a continuous mold space, and flanges closing the opposite edges of said mold space, means whereby said carriers may have simultaneous, similar movement imparted thereto, 20 means compacting and delivering composition cork to within said mold space, two chambers through which said mold forming elements are successively passed after receiving said composition cork, and means maintaining an elevated temperature in the first of said chambers, whereby composition cork within said mold forming elements will be successively subjected to a high temperature and to a relatively lower temperature.

3. An apparatus of the character described, 40 embodying therein two oppositely disposed, endless carriers, the adjacent reaches of which extend in substantially parallel relation to each other, a sequence of independent mold forming elements supported by said carriers respectively and adapted to be brought thereby so as to abut against each other, the elements upon said carriers respectively being spaced apart to form a continuous mold space, and flanges closing the 45 opposite edges of said mold space, means whereby said carriers may have simultaneous, similar movement imparted thereto, means compacting and delivering composition cork to within said mold space, means whereby said carriers are positively held against movement while said last named 50 means are operative to deliver composition cork to within the mold space, and a heated chamber through which said mold forming elements are passed after receiving said composition cork.

6. An apparatus of the character described, 65 embodying therein two oppositely disposed, endless carriers, the adjacent reaches of which extend in substantially par-

allel relation to each other, a sequence of independent mold forming elements supported by said carriers respectively and adapted to be brought thereby so as to abut against each other, the elements upon said carriers respectively being spaced apart to form a continuous mold space, and flanges closing the opposite edges of said mold space, a hopper for composition cork, a measuring device adapted to deliver cork from said hopper, a cylinder with which said measuring device communicates, a throat leading from said cylinder and opening into one end of the mold space formed by said mold forming elements, a piston mounted in said cylinder, means whereby said carriers may have simultaneous, similar movement imparted thereto, and a heated chamber through which said mold forming elements are passed after receiving 70 said composition cork. 75

5. An apparatus of the character described, embodying therein two oppositely disposed endless carriers, the adjacent reaches of which extend in substantially parallel relation to each other, a sequence of independent mold forming elements supported by said carriers respectively and adapted to be brought thereby so as to abut against each other, the elements upon said carriers respectively being spaced apart to form a continuous mold space, and flanges closing the opposite edges of said mold space, means compacting and delivering composition cork to within said mold space, driving means for said carriers including therein rotatable 80 members about which said carriers respectively pass, gears connecting members for the oppositely disposed carriers, a driving gearing operative upon one of said last named gears consisting of a Geneva gear 85 movement, and means actuating one of the elements of said Geneva gear movement, whereby said carriers are positively held against movement except during a part of each revolution of said driving means, means 90 synchronized with the actuation of said Geneva gear movement for actuating the means for compacting and delivering composition cork, and a heated chamber through which said mold forming elements are passed after 95 receiving said composition cork. 100

6. An apparatus of the character described, embodying therein two oppositely disposed endless carriers, the adjacent reaches of which extend in substantially parallel relation to each other, a sequence of independent mold forming elements supported by said carriers respectively and adapted to be brought thereby so as to abut against each other, the elements upon said carriers respectively being spaced apart to form a continuous mold space, and flanges closing the opposite edges of said mold space, a hopper for composition cork, a measuring device adapted to deliver cork from said hopper, a 110

cylinder with which said measuring device communicates, a throat leading from said cylinder and opening into one end of the mold space formed by said mold forming elements, a piston mounted in said cylinder, driving means for said carriers including therein rotatable members about which said carriers respectively pass, gears connecting members for the oppositely disposed carriers, a driving gearing operative upon one of said last named gears consisting of a Geneva gear movement, and means actuating one of the elements of said Geneva gear movement, whereby said carriers are positively held against movement except during a part of each revolution of said driving means, means synchronized with the actuation of said Geneva gear movement for actuating said piston and said measuring device, and a heated chamber through which said mold forming elements are passed after receiving said composition cork.

7. An apparatus of the character described, embodying therein two oppositely disposed, endless carriers, the adjacent reaches of which extend in substantially parallel relation to each other, a sequence of independent mold forming elements supported by said carriers respectively and adapted to be brought thereby so as to abut against each other, the elements upon said carriers respectively being spaced apart to form a continuous mold space, end flanges closing the opposite edges of said mold space, means whereby said carriers may have simultaneous, similar movement imparted thereto, means compacting and delivering composition cork to within said mold space, a heated chamber through which said mold forming elements are passed after receiving said composition cork, and backing members operative upon said mold forming elements while within said heated chamber to prevent separation of said elements as a result of expansion of the composition cork within the mold space.

8. An apparatus of the character described, embodying therein two oppositely disposed, endless carriers, the adjacent reaches of which extend in substantially parallel relation to each other, a sequence of independent mold forming elements supported by said carriers respectively and adapted to be brought thereby so as to abut against each other, the elements upon said carriers respectively being spaced apart to form a continuous mold space, end flanges closing the opposite edges of said mold space, means whereby said carriers may have simultaneous, similar movement imparted thereto, means compacting and delivering composition cork to within said mold space, two chambers through which said mold forming elements are successively passed after receiving said composition cork, means

maintaining an elevated temperature in the first of said chambers, whereby composition cork within said mold forming elements will be successively subjected to a high temperature and to a relatively lower temperature, and backing members operative upon said mold forming elements while within said heated chamber to prevent separation of said elements as a result of expansion of the composition cork within the mold space.

9. An apparatus of the character described, embodying therein two oppositely disposed sets of endless chains, the adjacent reaches of which extend in substantially parallel relation to each other, a sequence of independent mold forming elements supported by said chains respectively and adapted to be brought thereby so as to abut against each other, the elements upon said carriers respectively being spaced apart to form a continuous mold space, end flanges closing the opposite edges of said mold space, means whereby the space between said members is closed at the opposite ends thereof to complete the formation of said mold space, means whereby said carriers may have simultaneous, similar movement imparted thereto, means compacting and delivering composition cork to within said mold space, two chambers through which said mold forming elements are successively passed after receiving said composition cork, means maintaining an elevated temperature in the first of said chambers, whereby composition cork within said mold forming elements will be successively subjected to a high temperature and to a relatively lower temperature, and backing members operative upon said mold forming elements while within said heated chamber to prevent separation of said elements as a result of expansion of the composition cork within the mold space.

10. An apparatus of the character described, embodying therein two oppositely disposed sets of endless carriers, the adjacent reaches of which extend in substantially parallel relation to each other, a sequence of independent mold forming elements supported by said carriers respectively and adapted to be brought thereby so as to abut against each other, the elements upon said carriers respectively being spaced apart to form a continuous mold space, end flanges closing the opposite edges of said mold space, means whereby said carriers may have simultaneous, similar movement imparted thereto, a hopper for composition cork, a measuring device adapted to deliver cork from said hopper, a cylinder with which said measuring device communicates, a throat leading from said cylinder and opening into one end of the mold space formed by said mold forming elements, a piston mounted in said cylinder, means whereby said carriers are positively held against move-

ment while said piston is operative to deliver composition cork to within the mold space and receive movement while said cylinder is inoperative to so compact and deliver the composition cork, two chambers through which said mold forming elements are successively passed after receiving said composition cork, and means maintaining an elevated temperature in the first of said

chambers whereby composition cork within 10 said mold forming elements will be successively subjected to a high temperature and to a relatively lower temperature.

In witness whereof I have hereunto affixed my signature, this 24th day of April, 1923.

CHARLES E. McMANUS.
